UNITED STATES PATENT OFFICE

RICHARD E. BISSELL, OF CLEVELAND HEIGHTS, OHIO, ASSIGNOR TO THOMPSON PRODUCTS, INC., OF CLEVELAND, OHIO, A CORPORATION OF OHIO

FUEL LOSS INDICATOR

Application filed March 16, 1927. Serial No. 175,912.

My invention relates to methods of and devices for indicating the fuel loss in an internal combustion engine and is particularly adaptable for use in connection with the engine of a motor vehicle, its object being to enable the driver thereof to determine the character of the mixture supplied to the cylinders and thereby indicate to him improper conditions which result in fuel loss, when such conditions exist.

It is well known that the products of combustion of an internal combustion engine include combustible gases such as carbon monoxide, hydrogen and methane, even when the engine works at its maximum power efficiency. The quantity of such gases in the exhaust is in proportion to the richness of the mixture supplied to the cylinders, so that if the quantity of such gases in the exhaust were measured, the character of the mixture being supplied to the engine would be indicated. I have discovered a method and means for ascertaining relative quantities of such gases in the exhaust, which contemplate the withdrawal of a minor part of the exhaust gases, mixing them with air, burning the combustible constituents of the mixture in a closed chamber, and measuring the temperature in the vicinity of the heat produced by such combustion. As the temperature produced has a definite relation to the quantity of combustible constituents in the exhaust, it affords an index to the richness of the mixture supplied to the engine.

The annexed drawings and the following description set forth in detail certain means for carrying out my invention, the disclosed means, however, constituting but one of the various mechanical forms in which the principle of my invention may be employed.

In said annexed drawings:

Figure 1 represents a broken vertical axial section of an apparatus for practicing my invention and shown as applied to a motor vehicle.

Fig. 2 represents a detail view taken upon the plane indicated by line II—II of Fig. 1, and in the direction indicated by the arrows.

Fig. 3 represents an enlarged section taken upon the plane indicated by line III—III,

Fig. 1, and in the direction indicated by the arrows.

Fig. 4 represents a fragmentary section, similar to that of Fig. 1, showing a modified construction.

Fig. 5 represents a detail view taken upon the plane indicated by line V—V of Fig. 4.

In the illustrated embodiment, the exhaust duct 1 of a motor vehicle has connected therewith a pipe 2 which is connected at its other end to a pressure regulator 3 which may be of any well-known form, but as shown, consists of two chambers 4 and 5 divided by a horizontal partition 6. In the center of the partition is an opening 7 controlled by a valve 8 connected with a flexible diaphragm 9 pressed by a coiled spring 10, the tension of which may be regulated by an adjusting screw 11. A pipe 12 connects the upper chamber 5 to a combustion chamber 13 secured at one end to a plate 14 mounted on the dash board 15. The combustion chamber 13 has an inner lining of refractory heat insulating material 16, through which the pipe 12 passes at a point midway of the combustion chamber, into which is fixed a spark plug 18 provided with electrodes 19 and 20 which may be of ordinary construction; but electrode 20 is preferably constructed of a platinum wire which acts as a catalyst. The spark may be supplied from the usual ignition system of the engine, but it is preferred that a separate spark coil be employed connected to the usual battery and adapted to give a substantially continuous spark.

A temperature responsive member 21 is located in any convenient position to enable it to respond to the variation in temperature produced by combustion of the gases in the combustion chamber. As shown in Figs. 1 and 3, the temperature responsive means is located in the combustion chamber at the end opposite the spark plug 18, and consists of a spiral member built up of two metal strips having different coefficients of expansion, the outer end of which is connected with an anchor 22 fixed to the wall defining chamber 13. The inner end is fixed to a spindle 23 passing through and bearing in the end wall of the combustion chamber, and to the outer end

thereof is fixed a pointer 24, which may be made adjustable on the spindle for purposes of calibration, according to well-known practice. Beneath the pointer, on the face of the plate 14 is a scale 25 which may be calibrated 5 in any desired way according to the principles herein disclosed. The pointer and scale are protected by a transparent cover 26.

The gases passing from the pressure regulating chamber to the combustion chamber 10 are commingled with air, for which purpose the pipe 12 is provided with a centrally perforated diaphragm 27, and with air inlet openings 28 in advance of the diaphragm. Preferably the pipe is also provided with a 15 Venturi opening 29. The space in front of the diaphragm 27 is a mixing chamber in which the exhaust gas and air are commingled. The combustion chamber is provided with an outlet pipe 30 discharging into the 20 atmosphere.

The scale 25 is preferably so calibrated and arranged with relation to the pointer that the pointer will stand at a selected point when the combustible constituents carried into the 25 combustion chamber 13 are in that quantity which results from the use of the leanest mixture that will afford the maximum power efficiency. If the richness of the mixture is increased beyond this point, the exhaust gases 30 will contain a greater quantity of combustible gases of the nature indicated, such greater quantity will be burned in the combustion chamber and produce a higher temperature therein, which will be indicated accordingly 35 by the pointer. The pointer will advance over the scale in proportion to the richness of the mixture supplied to the engine. The operator will accordingly know when the mixture supplied to the engine is too rich, and, by the calibration of the scale, be informed of the degree thereof in excess of the proper mixture, and the mixture supplied to the engine may then be regulated accordingly. 40

The combustible constituents of the exhaust 45 gases burned in the combustion chamber constitute only a small proportion of the total volume and consequently flame produced by combustion is comparatively weak. The 50 principal function of the regulator is therefore to reduce the pressure of the exhaust gases so as to make it possible to introduce them into the combustion chamber at low velocity to avoid extinguishing the flame. The tension 55 on the regulator valve will preferably be so adjusted as to cause the gases to be delivered into the combustion chamber at a velocity as low as possible while securing the most effective combustion. The pressure 60 regulator also secures an average composition of exhaust gases resulting from a plurality of explosions of the engine. As the 65 gases pass from the regulator to the combustion chamber through a passage which remains fixed, the rate of flow of the gas into

the combustion chamber will be substantially constant for any setting of the pressure regulator, and while such a substantially constant rate of flow is desirable, it is not considered absolutely essential, it being of more 70 importance to deliver the gas into the combustion chamber at low velocity. In the instrument disclosed herein the gas is delivered against the end of the combustion chamber and in the vicinity where combustion is 75 effected, whereby its velocity is further reduced and its pressure increased, creating the most favorable conditions for combustion.

The chamber 4 of the regulator also functions to condense the stream in the exhaust gases, a valve 31 being provided which may remain slightly open or may be opened from time to time to draw off the water of condensation, by which means the gases are substantially deprived of their moisture, causing them to be delivered into the combustion 85 chamber in a substantially dry condition.

Operation.—The operation of the device will be apparent from the above description. As the exhaust gases issue through the exhaust duct 1 a portion thereof enter the lower chamber 4 of the pressure regulator, and thence through the opening 7 into the chamber 5 until the pressure in the latter chamber 90 exerted on the lower side of the diaphragm exceeds the pressure of the spring 10 whereupon the diaphragm 9 and valve 8 are caused to move upwardly and close the opening. When the pressure in the chamber 5 is reduced, more gas is admitted from chamber 4 and thus a substantially constant pressure is maintained in the chamber 5. From the chamber 5 the gas passes to the combustion chamber 13, being commingled with a proper amount of air at an intermediate point. The 95 commingled gases are directed by the end of pipe 17 into the spark gap of the sparking device by which combustion is effected, as more fully described in a patent granted to Thompson and Bissell, No. 1,605,484, dated 100 November 2, 1926. The products of combustion pass rearwardly about the coil 21 and to the outlet pipe 30 to atmosphere. The expansion of the coil gives motion to the pointer 105 24 which moves over the scale 25 and thus indicates the character of combustible mixture which is being supplied to the engine. 110

In the modified form of the device shown in Figs. 4 and 5, I have substituted a thermometer 32 for the temperature indicator previously described. The tube of the thermometer is bent so that the mercury bulb lies within the combustion chamber and the graduated portion is located so as to be visible to the driver. 120

Many variations may be made of the various features of the process and apparatus without departing from the spirit of the invention. It is therefore to be understood 125 that the invention is not confined to the de- 130

tails shown but embraces all changes and modifications falling within the terms of the appended claims.

What I claim is:

5 1. In a device for indicating the character of a combustible mixture supplied to an internal combustion engine comprising, in combination, a combustion chamber, means for mixing a minor part of the exhaust gases 10 from the engine with air, means for introducing the commingled gases into the combustion chamber at low velocity, a sparking device for effecting the combustion of the commingled gases, and indicating means responsive to the temperature in the combustion chamber.

2. In a device for indicating the character of a combustible mixture supplied to an internal combustion engine, comprising, in combination, a combustion chamber, means for mixing a minor part of the exhaust gases from the engine with air, means for introducing the commingled gases into the combustion chamber at low velocity, a substantially continuous sparking device for effecting combustion of the commingled gases, and indicating means responsive to the temperature in the combustion chamber.

3. In a device for indicating the character of a combustible mixture supplied to an internal combustion engine comprising, in combination, a combustion chamber, means for mixing a minor part of the exhaust gases from the engine with air, means for introducing the commingled gases into the combustion chamber at low velocity, a sparking device including a catalytic wire for effecting combustion of the commingled gases, and indicating means responsive to the temperature in the combustion chamber.

4. In combination, in a motor vehicle including an internal combustion engine and a dash, an auxiliary combustion chamber, means for conveying exhaust gases of the engine to said chamber, means for regulating the flow of gases to said chamber, means for mixing air with said gases, sparking means for effecting combustion of the commingled gases in said chamber, temperature responsive means in said chamber, and indicating means on said dash connected to the temperature responsive means for indicating the character of the combustible mixture supplied to said engine.

5. In a device for indicating the character of a combustible mixture supplied to an engine, an auxiliary combustion chamber, a pressure regulator connected thereto, means for conveying a part of the exhaust gases of the engine to said regulator, said regulator controlling the flow of said conveyed gases to said chamber, means for effecting combustion of the gases delivered to said chamber, and indicating means responsive to the temperature in said chamber and calibrated in

terms of richness of mixture supplied to said engine.

6. The combination with a combustion engine of means for receiving a part of the exhaust gases discharged from said engine, 70 means for burning said part of said gases, means responsive to the temperature of the burning gases, and a device operated by said temperature responsive means for indicating the richness of a combustible mixture 75 supplied to said engine.

7. The method of determining the character and richness of the combustible mixture supplied to an internal combustion engine which consists in withdrawing a predetermined quantity of gas from the exhaust gases of the engine, causing combustion of said withdrawn exhaust gas and utilizing the heat given off by said combustion to determine in terms of richness the character of mixture 85 being supplied to the engine.

8. The method of determining the character and richness of the combustible mixture supplied to an internal combustion engine which consists in withdrawing a quantity of 90 gas from the exhaust gases of the engine, commingling air with said withdrawn gas, causing said commingled gases to flow at a low velocity, burning the commingled gases and utilizing the heat given off during the 95 burning of said commingled gases to determine in terms of richness, the character of mixture being supplied to the engine.

Signed by me this 26 day of February, 1927. 100
